RECEIVING SYSTEM

Rene A. Braden, Merchantville, N. J., assignor to
 Radio Corporation of America, a corporation of
 Delaware

Application January 9, 1932. Serial No. 585,647

5 Claims. (Cl. 250—20)

My present invention relates to electrical wave receiving systems, and more particularly to novel methods of, and means for, amplifying the amplitude of the carrier wave of intelligence modulated carrier energy with respect to the side bands of such carrier energy.

5 It has been pointed out in my co-pending application, Serial No. 585,646 filed January 9, 1932, that in the reception of modulated carrier energy there exists various situations where it is extremely desirable to effect amplification of the carrier amplitude with respect to side band amplitude after the carrier energy has been collected. Briefly, the following three situations have been cited as cases where the aforementioned carrier amplification is effected to great advantage:

(1) Interference between broadcasting stations may be considerably reduced by broadcasting energy from stations in such a manner that the side bands are transmitted at full amplitude, while the carrier wave is transmitted at reduced amplitude, the carrier wave of the received energy being amplified more than the side bands at the receiving point so as to bring the carrier up to normal amplitude at the detector input.

(2) Selective carrier fading and general signal fading in short wave reception resulting from natural phenomena may be corrected by separating the carrier wave from the side bands, and amplifying the carrier from sub-normal amplitude to normal amplitude.

(3) The production of harmonics in the output of the detector, which is caused by a high degree of modulation of carrier wave, may be considerably minimized by elevating the carrier amplitude from normal to super-normal value in order to reduce the degree of modulation of the carrier wave.

40 Various arrangements are disclosed in my said co-pending application for attaining the aforementioned objects. One of the arrangements shown in the said application discloses the amplification of the carrier wave from sub-normal amplitude to normal amplitude in a separating path which includes a carrier frequency oscillator, selective fading being compensated for by this arrangement. Furthermore, it has been shown in the aforementioned application that the various arrangements disclosed therein could be 45 successfully employed for reducing the degree of modulation of the carrier wave, and thereby minimizing the production of harmonics in the detector output circuit of a radio receiver.

50 In the present application I have disclosed ad-

ditional arrangements for effecting increase of carrier amplitude with respect to side bands, for the purposes described above, and particularly for reducing the amount of harmonics produced in the detector output circuit of a receiver.

Accordingly, it may be stated that it is one of the main objects of my present application to provide a method of separating the carrier wave of received modulated carrier energy from its side bands, treating the separated carrier wave in such a manner with respect to the side bands that the carrier amplitude is elevated from its original value, the amplitude elevation being accomplished in a path including a carrier frequency oscillator.

Another important object of the present invention is to provide a method of rectifying modulated carrier energy with a minimum production of harmonics in the detector output circuit, the collected carrier energy being diverted through two paths, one of the paths including a distorting detector, the outputs of both paths being combined in such a manner that distortion produced in the first path is substantially compensated for by distortion produced in the second path.

Still other objects of the present invention are to improve generally the efficiency of radio reception, and to particularly provide a radio receiver wherein collected modulated carrier energy is diverted into two paths, one of the paths including means for compensating for an undesirable characteristic existing in the energy in the first path thus resulting in a receiver which is not only capable of reducing detector distortion due to harmonic production in the detector output to a great extent, but is also capable of reliable reception of signal energy wherein the carrier is received at subnormal amplitude.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 diagrammatically shows a radio receiver embodying one form of the present invention,

Fig. 2 diagrammatically shows another embodiment of the invention,

Fig. 3 shows still another form of the invention in diagrammatic manner.

Referring now to the accompanying drawing

wherein like characters of reference indicate the same parts in the different figures, there is shown in Fig. 1 a radio receiver system wherein modulated carrier energy is collected, amplified and detected for utilization in any well known manner, numeral 1 designating in conventional manner a source of signal energy, as for example an antenna system. It is to be understood that the energy collected at the source 1 may be composed of side bands transmitted at full amplitude, and a carrier wave at much reduced amplitude, or a carrier wave at normal amplitude.

The reception method shown in Fig. 1 is capable of compensating for disadvantages inherent in the reception of carrier energy wherein the carrier amplitude has either of the aforementioned two values. It has already been pointed out that detection of signal energy wherein the carrier is collected at sub-normal amplitude results in distortion, while detection of signal energy wherein the carrier exists at normal amplitude may result in the production of harmonics in the detector output circuit because of a high degree of modulation of the carrier wave.

25 The reception method in Fig. 1, accordingly, comprises a path for amplifying the carrier wave independently of its associated side bands to normal or super-normal amplitude as desired. The construction and operation of the arrangement shown in Fig. 1 will be explained in connection with the reduction of the degree of modulation of the carrier wave. The detector circuit of the receiving arrangement includes an electron discharge device 2 arranged for grid bias detection by means of a bias source C, the anode of the device being energized from a source B. The input of the detector tube includes a tuning element, as a variable condenser 3, and the detector receives energy, through a coupling M_2 , from a multi-stage radio frequency amplifier 4 whose input includes a tuning device, such as a variable condenser 5, for the selection of the desired carrier wave frequency. The input of the radio frequency amplifier 4, is coupled, as at M_1 , to the source of signal energy. The output of the detector 2 may be amplified by the usual audio frequency amplifier 6, and then utilized in any conventional manner, as by head phones, a loud speaker, or the like.

30 It is well known that rectification of modulated signals produces not only audio frequency currents of the original modulation frequency, but also second, and higher harmonics, as well as sum frequencies. The amount of extra frequencies produced in the detector output depends on the degree of modulation of the carrier wave. By reducing the degree of modulation, the amount of harmonics produced in the detector output will be considerably minimized with resulting improved detection. To accomplish this reduction of the degree of modulation, a path is provided between the amplifier 4 and the detector input, the path including a synchronized oscillator, conventionally shown and designated by the reference numeral 7, the oscillator being tuned, as by a variable condenser 8, approximately to the frequency of the carrier wave.

35 The oscillator is held synchronized by coupling to the output of the amplifier 4. It is to be understood that the portion of the path leading to the coupling point M_3 is connected to the output of the amplifier 4. The synchronized oscillator 7 is not shown in its structural details, since any type of oscillator well known to those skilled in the art may be employed. Current from the oscil-

lator 7 is fed into the detector 2 with the output of the amplifier 4.

The oscillator current constitutes an addition to the carrier frequency current, and in fact reduces the degree of modulation. The oscillator current is fed through a suitable phase-shifting device, if necessary, so that the additional current will be in phase with the carrier from the amplifier 4, and thus increase the total carrier current instead of subtracting from it. However, if the oscillator output is made sufficiently strong, the phase relation can be disregarded, and the original carrier current from the amplifier 4 will be a small part of the whole current of carrier frequency impressed upon the input of the detector 2. For simplicity of operation, the tuning devices 3, 5 and 8 may be arranged for uni-control by a single mechanism 9.

40 It should be obvious from the foregoing explanation of the reception method shown in Fig. 1 that proper design of the oscillator 7 will result in supplying oscillator current of carrier frequency in such amount that the original carrier wave amplitude is changed from sub-normal amplitude to normal amplitude, or even from sub-normal amplitude to super-normal amplitude for purposes already referred to in detail.

45 In Fig. 2 there is shown another embodiment of the present invention wherein a circuit for increasing carrier amplitude is disposed between the usual radio frequency amplifier, and the detector input. The circuit shown in Fig. 2 is identical with that shown in Fig. 1 except for the fact that the carrier frequency oscillator 7 is disposed between the amplifier 4 and the input of the detector 2 so that the energy from the amplifier 4 is transmitted to the detector input through the oscillator. The detector circuit is arranged for grid leak detection in this figure instead of for grid bias detection, and has energy impressed upon it for detection through the coupling M_2 from the output circuit of the carrier frequency oscillator which includes the tube 10.

50 The oscillator circuit is of a type well known to those skilled in the art and includes in the anode circuit of the tube a path for feeding back energy at carrier frequency to its tuned input circuit. A source B' supplies energy for the anode of the oscillator tube 10 through a radio frequency choke coil 11, the usual blocking condenser 12 being disposed between the source B' and the coupling transformer primary 13, it being understood that the inductance coil 13 is connected in series with the feed back coil 14. The latter coil is inductively coupled with the coupling transformer secondary coil 15 disposed in the input circuit of the oscillator 10.

55 The carrier frequency oscillator actually comprises an amplifier having feed back coupling sufficient to produce oscillations, the amplifier being synchronized for oscillation at the carrier wave frequency by carrier wave current fed into it from the amplifier 4. The side bands are amplified, and passed on to the detector which also receives a large carrier frequency voltage from the oscillating tube 10. It will thus be seen that the arrangement shown in Fig. 2 comprises a method for increasing carrier amplitude in a path identical with the path through which the side bands are transmitted, the transmission path including an oscillator arranged to amplify the carrier considerably more than the side bands. The oscillating amplifier in Fig. 2 is highly selective, so that the amplification of the carrier is very much greater than that of the side bands.

The arrangements shown in Fig. 2 can clearly be employed for attaining any of the three objects noted heretofore, and is clearly adapted to reduce the degree of modulation of the carrier 5 wave so as to diminish harmonic production in the output of the detector circuit.

In Fig. 3 there is shown still another form of the present invention wherein after collection of modulated carrier energy at a source 1, and amplification at radio frequency at 4, the amplified energy is diverted into two paths, part of the output of the amplifier 4 being transmitted through a detector circuit, including the tube 2 arranged for grid bias detection in the usual manner. The 10 input circuit of the detector tube 2 includes a tuning device, as a variable condenser 3, and is coupled, as at M_2 , to the output of the amplifier 4. The output of the detector tube 2 is coupled, as at M_4 , by means of an audio frequency transformer to the input circuit of an audio frequency 15 amplifier, not shown.

The aforementioned second path through which the output of the amplifier 4 is diverted includes a second detector circuit provided with a tube 2' arranged for grid bias detection in the usual manner, the input circuit of the tube 2' being tuned by the variable condenser 3', the coupling transformer M_5 transmitting energy from the output of the amplifier 4 to the input of the 20 detector tube 2'. In order to reduce the carrier amplitude in the path including the detector tube 2', any conventional arrangement may be employed. For purposes of illustration, such a device is shown as comprising a resonant circuit 25 which includes an inductance coil 20 shunted by a variable condenser 21, the inductance coil 20 being coupled to the secondary inductance coil 22 of the coupling transformer M_5 .

The resonant circuit including the coil 20 and condenser 21 is sharply resonant to the carrier 40 wave frequency, while the resonant input circuit of the tube 2' is arranged for broad tuning by inserting a resistor 23 therein in series between the coil 22 and the condenser 3'. The tuning 45 condensers 3, 21, 3', are arranged for uni-control, as at 24, whereby at resonance the sharply tuned circuit including the inductance 20 and the condenser 21 will absorb energy at carrier frequency from the input circuit of the detector tube 2' 50 thereby effectively reducing the carrier amplitude.

The output circuit of the tube 2' is coupled to the input of the audio amplifier through an audio frequency transformer coupling M_6 , the primary coil 25 of which coupling is wound in a manner opposite to that of the primary coil of the audio frequency transformer M_4 . The detected outputs of tubes 2 and 2' are combined so that the energy from the output of tube 2' subtracts from the combined energies. The strength of the output of tube 2' is adjusted, as in the input circuit thereof by using the sharply tuned absorbing circuit 20, 21 so that the amount of combination frequency and harmonics is substantially the same as produced in the output of detector tube 2.

The fundamental frequency in the output of tube 2' will, of course, be smaller than in the output of detector tube 2. Thus, subtracting the energy produced in the output of tube 2' from that produced in the output of tube 2 will remove a large part of the extra frequency currents, leaving undistorted currents which are then amplified and utilized in any desired manner.

The action of the circuit shown in Fig. 3 may be explained in still another manner. In fact, there is disposed between the audio amplifier, or other utilizing means, and the audio frequency amplifier output two detector circuits. One of these detector circuits is of the usual and conventional type. The other detector circuit is exactly the same as the first detector circuit, but differs therefrom in including in the input circuit thereof a device for reducing the carrier amplitude. However, it should be observed that in both these detector circuits the same amount of distortion will occur, although less undistorted signal energy will be produced in the detector circuit which includes the carrier amplitude reducing device.

Then, by combining the outputs of the two detector circuits in subtractive fashion, it will be obvious that the distortion effects produced in both detector circuits, being equal and opposite, will balance out, leaving less undistorted signal energy than could be obtained by the use of the usual detector circuit itself. In other words, although a certain amount of undistorted signal energy is lost by this method, yet the distortion currents, such as harmonics and other extra frequency currents, are eliminated from the detector circuit by providing a second detecting circuit for balancing out the distortion currents. This arrangement is, of course, adapted for use 100 in connection with the suppression of harmonics in the output circuit of a detector, rather than for the purpose of increasing carrier amplitude to accomplish the suppression, or for eliminating disadvantages inherent in receiving carrier energy with carrier amplitude below normal.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. A receiving circuit comprising a radio frequency amplifier, a detector circuit, a carrier frequency oscillator having its input circuit coupled to the output of the amplifier and its output circuit coupled to the input of the detector, the oscillator circuit providing a single path between said amplifier and said detector both for the side band energy and the carrier energy, and being so arranged that carrier wave energy is amplified to a greater extent than the side band energy.

2. In combination, a source of signal energy, a radio frequency amplifier, a detector circuit coupled to the amplifier, a second detector circuit having its input coupled to the said amplifier, means for combining the outputs of both detector circuits in subtractive manner, and additional means for reducing the carrier amplitude in the second detector circuit.

3. In a radio receiver, an energy collector adapted to receive modulated carrier energy, an amplifier having input and output circuits, the input circuit of said amplifier being coupled to said energy collector, a detector and an oscillator each having input and output circuits, said oscillator being arranged to generate oscillations of carrier frequency, the input circuits of both said detector and oscillator being separately coupled to the output circuit of said amplifier in such manner that both said detector and said oscillator

- have impressed upon them the signal carrier frequency, and the output circuit of said oscillator being coupled to the input circuit of said detector whereby the carrier oscillations from said oscillator and from said amplifier additively combine in said detector, said oscillator providing a path for amplifying the carrier wave independently of the associated side bands; and a utilization circuit coupled to the output of said detector.
- 10 4. In a radio receiver, a modulated carrier energy amplifier, a detector circuit, a path extending from the output of said amplifier to the input of said detector arranged to pass both the

carrier and its associated side bands, and means in said same path tuned to the carrier for amplifying the carrier independently of the side bands.

5. In a radio receiver, an amplifier, a detector circuit, a path extending from the output of said amplifier to the input of said detector arranged to pass both the carrier and its associated side bands, said path including an electron discharge device oscillator whose input circuit is coupled to the output of said amplifier and whose output circuit is coupled to the input of said detector.
